FIG. 3

INVENTOR.

Frederick Graf.
BY Morsell & Kearny

ATTORNEYS.

UNITED STATES PATENT OFFICE.

FREDERICK GRAF, OF MILWAUKEE, WISCONSIN

SUPPORTING MEANS FOR IRONING BOARDS.

Application filed September 6, 1921. Serial No. 498,840.

To all whom it may concern:

Be it known that I, FREDERICK GRAF, a citizen of the United States, and resident of Milwaukee, in the county of Milwaukee, 5 and State of Wisconsin, have invented new and useful Improvements in Supporting Means for Ironing Boards, of which the following is a description, reference being had to the accompanying drawings, which are a part of this specification.

This invention relates to improvements in supporting means for ironing boards.

One of the objects of the invention is to provide novel and rigid supporting means 15 for an ironing board of such construction that the board may be positioned vertically when not in use, but readily swung to the horizontal position when it is desired to use it.

20 A further object of the invention is to provide supporting means for the ironing board in the form of a cabinet which is adapted to be positioned against or built into the wall of a room and which is provided with novel mounting means for the ironing board so that the board may be positioned vertically inside the cabinet when not in use or conveniently swung to the horizontal position when it is desired to use it, 25 whereby when the board is not in use, it is hidden from view and the padding thereon is kept clean ready for use whenever desired.

In the preferred form of my invention the supporting member or cabinet is formed or 30 provided with a pair of oppositely disposed, vertically extending guideways each of which is formed at its upper end with a rounded laterally offset and downwardly extending portion, the guideways being adapted to receive trunnions carried by the board at one end so that that end of the board is pivotally and slidably connected with the supporting member or cabinet, supporting means being provided for the other end of 35 the board, preferably in the form of a leg, the ends of which are hingedly connected to the board and the supporting member or cabinet, respectively, whereby the board may be swung into vertical position when not in use but readily swung to the horizontal position when it is desired to use it; and a further object of the invention is to provide 40 means to lock the first mentioned end of the board against movement relative to the supporting member or cabinet when the board is in the horizontal position.

My invention contemplates the provision of a second board, preferably a relatively small board, on which sleeves and small articles may be conveniently ironed which is hingedly connected at one end to the supporting member or cabinet; and a further object of the invention is to provide a supporting leg for said small board which is so connected to said board and the supporting member or cabinet that when the large board and the small board are in horizontal position, said supporting leg bears tightly against the adjacent end of the large board and effectively locks that end of the large board against movement relative to the supporting member or cabinet.

The invention consists in the novel constructions and arrangements to be herein-after described and claimed for carrying out the above stated objects and such other objects as will appear from the following description of a certain preferred embodiment illustrated in the accompanying drawings wherein—

Fig. 1 is a front elevational view of a cabinet built into a wall and adapted to form the supporting means for the ironing board;

Fig. 2 is a sectional view taken on the line 2—2 of Fig. 1, the two ironing boards being in vertical position and enclosed within the cabinet;

Fig. 3 is a view similar to Fig. 2 but showing the ironing boards in horizontal position ready for use;

Fig. 4 is a sectional view, on an enlarged scale, taken on the line 4—4 of Fig. 2; and

Fig. 5 is a detail view of a portion of one of the guideways showing particularly the offset portion provided at the upper end thereof.

Like characters of reference designate like parts in the several views.

Referring now to the drawings, it will be seen that the ironing boards are mounted in a cabinet which serves both as a supporting means and as an enclosure means for the boards. It will be apparent, however, as the description of my invention proceeds, that the ironing boards may be readily mounted upon a suitable supporting member which need not be in the form of a cabinet.

The cabinet comprises vertically extending side walls 8, a top member 9, a bottom member 10, and a back member 11 all connected together in any desired manner and

- preferably built into the wall 12 of a room. After the cabinet is secured in place in the wall, a suitable casing 13 is provided around the cabinet to cover the joint between the cabinet and the wall. The cabinet is provided with a door 14 which is connected at one side by means of hinges 15 to the adjacent portion of the casing 13 and is provided at the other side with a knob 16.
- 10 The side walls 8 of the cabinet are provided with oppositely disposed, vertically extending guideways 17 the upper ends of which terminate in a rounded laterally offset and downwardly extending portion 18, see Fig. 5. The inner end of the ironing board 19 is secured to a transverse strip 20 which carries a pair of trunnions 21 adapted to project into the guideways 17. The outer or opposite end of the board 19 is supported, 20 when in horizontal position, by a supporting member, preferably consisting of a pair of legs 22 each of which are hingedly connected at one end to the bottom of the board and at the other end to the bottom of the cabinet, 25 transversely extending brace bars 23 being provided for the legs 22.
- The inner end of the sleeve board 24 is hingedly connected to a transversely extending strip 25 which is secured in any desired 30 manner to the back of the cabinet. The middle portion of the board 24 adjacent its inner end is cut out, as at 26, to provide room, when the board 24 is swung to the vertical position, for a supporting leg 27 hingedly connected at one end to the bottom of the board 24 the other end of which is provided with trunnions 28 adapted to operate in vertically extending guideways 29 provided in the side walls of the cabinet.
- 40 It will now be apparent that when the parts are in the position shown in Fig. 2 and the door 14 of the cabinet is opened, the board 19 may be moved from the vertical position into the position shown in Fig. 3, 45 the trunnions 21 riding upwardly in the guideways 17 and slipping into the offset portions 18 thereof. The small board 24 may now be moved from the position shown in Fig. 2 to the position shown in Fig. 3.
- 50 When the board 24 is in the position shown in Fig. 3, the supporting leg 27 bears against the inner end of the board 19 and prevents any backward movement of the board 19 relative to the cabinet so that the board 19 is effectively locked with its trunnions in the offset portions 18 of the guideways. The construction is extremely simple and is very substantial, firmly supporting both boards when in the horizontal position. The boards may be readily moved from one position to the other and when enclosed within the cabinet they are kept in a clean and sanitary condition, and, of course, are hidden from view.
- A shelf member 30 is preferably provided in the upper portion of the cabinet on which the iron and the iron stand may be placed when not in use.
- I claim:
1. In combination with a supporting member having opposite side members provided with vertically extending guide grooves terminating at their upper ends with rounded laterally offset and downwardly extending portions to form locking parts, an ironing board having inner end opposite trunnions which extend into said guide grooves, said trunnions automatically entering the locking portions of the grooves when the board is moved endwise in one direction and automatically disengaging said locking portions of the grooves when the board is moved in the other direction, a leg member hinged at its lower end to the lower portion of the supporting member and having its upper end hinged to the outer end portion of the ironing board, and an auxiliary means for locking the board in operative position.
2. In combination with a supporting member having a bottom portion and opposite side portions provided with vertically extending guide grooves terminating at their upper ends in rounded outwardly and downwardly offset locking portions, an ironing board having inner end opposite trunnions which extend into said guide grooves, said trunnions automatically entering the locking portions of the grooves when the board is pulled outwardly and automatically disengaging the said locking portions of the grooves when the board is pushed inwardly, and a leg member hinged at its lower end to the bottom portion of the supporting member and having its upper end hinged to a medial portion of the ironing board.

In testimony whereof I affix my signature.
FREDERICK GRAF.
